His Attorney.

UNITED STATES PATENT OFFICE

CHARLES F. SCHWENNKER, OF SCHENECTADY, NEW YORK, ASSIGNOR TO GENERAL ELECTRIC COMPANY, A CORPORATION OF NEW YORK

BUFFER FOR ELECTRIC SWITCHES

Original application filed January 5, 1924, Serial No. 684,669. Patent No. 1,569,683, dated January 12, 1926.
Divided and this application filed November 5, 1925. Serial No. 67,137.

My invention relates to electric switches and more particularly to a buffer arrangement adapted for checking movement of the moving parts of the switch. My invention 5 also relates to the structure of an improved buffer which is simple in construction, easily adjusted and effective to check an operating member in each of two directions of movement.

10 The present application is a division of my copending application, Serial No. 684,669, filed January 5, 1924 now Patent No. 1,569,683, issued January 12, 1926 for an electric switch.

15 My invention will be better understood from the following description taken in connection with the accompanying drawing, and its scope will be pointed out in the appended claims.

20 In the drawing Fig. 1 is a vertical sectional view of a fluid break switch involving my invention and Fig. 2 is a detail view.

In the drawing I have shown by way of example a fluid break switch in which the operating mechanism is located within the enclosing structure of the switch. This structure comprises the tank 1 and the top casing 2 secured together by bolts 3. Through the cover 4 of the casing extend the two insulator bushings 5, to the inner ends of which are secured the stationary contacts 6. The bridging contact member 7 cooperates with the contacts 6 to open and close the circuit connected therewith. The operating rod 8 terminates at its upper end in a ferrule 9 through which extends the pin 10. The switch actuating mechanism, a portion only 25 of which is illustrated, includes the bifurcated lever 12 through the ends of the two

30 sulator bushings 5, to the inner ends of which are secured the stationary contacts 6. The bridging contact member 7 cooperates with the contacts 6 to open and close the circuit connected therewith. The operating rod 8 terminates at its upper end in a ferrule 9 through which extends the pin 10. The switch actuating mechanism, a portion only 35 of which is illustrated, includes the bifurcated lever 12 through the ends of the two

40 arms of which pass the pin 10, and the link 13 pivoted to the lever 12 and to a stationary point 14 by means of which the operating rod is caused to move in a straight line. Each arm of the lever 12 has an outwardly extending

45 flange 15 having an elongated opening for receiving one of the screw-threaded rods 16. Heads 17 on these rods limit the downward movement of the lever. Directly over the operating rod 8 is the hollow bracket 18 shown secured to the cover 4 by bolts 19. The

flanged button 20 rests in the lower portion of the bracket 18 and the bar 21 extends through transverse slots formed in the upper portion thereof. Between the button 20 and the bar 21 are shown a series of felt disks 22, 55 which form the cushioning means. The rods 16 are threaded through the bar and abut the under side of the cover. When the switch is tripped open the downward movement of the operating parts is checked by the felt 60 disks 22, when the lever 12 reaches the heads 17 of the rods 16. Similarly when the switch is closed, the upward movement of the parts is checked by the same disks when the pin 10 engages button 20. By turning the rods 16 65 the felt disks may be given the necessary initial compression to give them the desired degree of hardness.

It will be noted that with the construction I have disclosed, the same set of disks is used 70 to check or cushion both the opening and the closing movement of the switch mechanism and also that adjustment of the initial compression of the disks does not affect the length of stroke of the switch, nor does it affect 75 either of the limiting positions of the movable contact member. The latter is of particular importance since as a result damage to the contact brushes due to overtravel of the parts in the closing movement may be 80 avoided.

While I have described only one embodiment of my invention, I do not wish to be limited to the particular form shown and described, as it will be apparent that many 85 modifications therein may be made without departing from the scope of my invention as set forth in the appended claims.

What I claim as new and desire to secure 90 by Letters Patent of the United States is:

1. An electric switch having a movable contact member and a buffer for checking movement thereof comprising a cushioning member, a support therefor, means for compressing the cushioning member by the movable member when the latter reaches predetermined positions in its movement in opposite directions and means whereby the initial compression of the cushioning member may 100

be varied without changing said predetermined positions.

2. An electric switch comprising a movable contact member having limiting positions of movement, a buffer therefor comprising a cushioning member, means whereby the cushioning member is stressed by both the forward and the return movement of the contact member, and means for varying the initial stress of said cushioning member without affecting said limiting positions.

3. An electric switch comprising a contact operating member, and a buffer comprising a support, a fixed cushioning member carried thereby, means for putting said member under initial compression and means cooperating therewith whereby the cushioning member is further compressed by the opening movement and by the closing movement of the operating member.

4. An electric switch comprising a movable contact, an operating member therefor, and a buffer having a cushioning member and a lost motion connection with the operating member, means for giving the cushioning member a permanent initial stress and means whereby the cushioning member is stressed an additional amount by the operating member when the latter reaches either end of its movement.

5. An electric switch comprising a switch operating member, a buffer comprising a fixed cushioning member, adjustable means engaging opposite sides of the cushioning member for giving the member a permanent initial compression, and means engaging said adjustable means whereby movement of the operating member beyond a predetermined point causes further compression of the cushioning member.

6. An electric switch comprising a contact operating member, means for limiting the closing and the opening movement thereof comprising a cushioning member, and means for varying the initial compression of the cushioning member without affecting the final limits of movement of the operating member.

7. An electric switch comprising a contact operating rod, means for moving the rod longitudinally to close and open the switch, and a buffer for limiting the movement of the rod, said buffer comprising a cushioning member, a support therefor, a pair of members between which the cushioning member is clamped, one of said members being adapted to be engaged by the operating rod when the switch reaches closed circuit position, and means connected with the other of said members adapted to be engaged by the operating rod when the switch reaches open circuit position.

8. An electric switch having a fixed contact, a cooperating contact arranged to have a definite opening and closing movement rela-

tive thereto, and a buffer for the movable contact comprising a single cushioning member constructed and arranged to cushion the movable contact at the end of both its opening movement and its closing movement.

In witness whereof, I have hereunto set my hand this 4th day of November, 1925.

CHARLES F. SCHWENNKER.
